UNITED STATES PATENT OFFICE.

A. WARNER, OF CLEVELAND, OHIO.

IMPROVED COMPOSITION FOR LEMONADE.

Specification forming part of Letters Patent No. 37,314, dated January 6, 1863.

To all whom it may concern:

Be it known that I, ASHER WARNER, of Cleveland, in the county of Cuyahoga and State of Ohio, have invented new and useful Improvements in Compound Extract of Lemon; and I do hereby declare that the following is a full and complete description of the ingredients used and the manner of compounding the same.

I take two pounds of loaf-sugar broken into small lumps and drop upon it uniformly one ounce of the oil of lemon. After an interval of fifteen or twenty minutes I add to it, in a clean mortar, one pound of tartaric acid and three ounces of citric acid and triturate the whole together, forming an intimate mixture. It is now put in bottles of suitable size—say of four ounces each—and tightly corked, and the compound is ready for use.

In making lemonade it is only necessary to

sweeten a tumbler of water and add to it from ten to twenty grains of the compound to suit the taste.

This compound can be used in pastry-cooking with every desired facility and convenience. It is admirably adapted to hospital purposes, and for most uses is more economical than the lemon fruit. It is concentrated in form and not subject to decay.

What I claim as my improvement, and desire to secure by Letters Patent, is—

The herein-described compound, consisting of loaf-sugar, oil of lemon, tartaric acid, and citric acid, prepared and combined substantially as and in the proportions herein set forth.

ASHER WARNER.
